UNITED STATES PATENT OFFICE.

WILLIAM BOGGS, OF NEW YORK, N. Y.

DESIGN FOR PAPER COLLARS, CUFFS, &c.

Specification forming part of Design No. 2,135, dated July 18, 1865.

To all whom it may concern:

Be it known that I, WILLIAM BOGGS, of the city, county, and State of New York, have invented a new and Improved Design for a Border for Paper Collars and Cuffs; and I do hereby declare that the following is a full, clear, and exact description thereof, which will enable those skilled in the art to make and use the same, reference being had to the accompanying drawings, forming part of this specification, in which—

Figure 1 represents a "turn-over" collar having my improved design printed thereupon. Figs. 2 and 3 represent an eared collar, or that kind of collar only a part of which turns over, having my improved design printed thereupon. Figs. 4, 5, and 6 represent a wristband or cuff having my improvement printed thereupon.

Similar letters of reference indicate corresponding parts.

My improved ornamental design consists of an ornamental design or band or border, A, stamped or printed in any desired color upon the edge of the collar or cuff, and an ornamental row of dots, B, also stamped or printed in any desired color upon the edge of the cuff or collar, as shown.

I claim as new and desire to secure by Letters Patent—

The within-described ornamental design for a border for paper collars and cuffs.

WILLIAM BOGGS.
